UNITED STATES PATENT OFFICE.

LUTHER E. JEROME, OF NEW HAVEN, CONNECTICUT, ASSIGNOR TO THE
NEW HAVEN CLOCK COMPANY, OF SAME PLACE.

CLOCK-DIAL.

SPECIFICATION forming part of Letters Patent No. 241,988, dated May 24, 1881.

Application filed April 16, 1881. (No model.)

To all whom it may concern:

Be it known that I, LUTHER E. JEROME, of New Haven, in the county of New Haven and State of Connecticut, have invented a new Improvement in Clock-Dials; and I do hereby declare the following, when taken in connection with the accompanying drawings and the letters of reference marked thereon, to be a full, clear, and exact description of the same, and

10 which said drawings constitute part of this specification, and represent, in—

Figure 1, a front view; Fig. 2, a rear view; Fig. 3, a transverse section enlarged.

This invention relates to an improvement in that class of clock-dials which are provided with a second-hand, the object being to recess the dial and ornament the margin of said recess; and it consists in cutting a circular opening through the dial and setting therein a cup-shaped smaller dial, the edge of the cup molded so as to overlap onto the face of the main dial, as more fully hereinafter described.

A represents the main dial, of the usual form. At the point where the second-pointer dial is required I cut a circular opening, *a*, a little larger in diameter than the second-pointer dial is required to be.

B is the second-pointer dial, which is struck from sheet metal into cup shape, as seen in Fig. 3, the external diameter of the cup corresponding to the diameter of the opening *a* through the dial. The edge of the cup is turned outward and so as to overlap onto the

surface of the principal dial to cover the joint between the two. This edge may be molded in any desirable shape to form a margin around the second-dial. This cup-shaped dial produces the best effect to be made from brass and retain that color in contrast with the white of the principal dial. It is secured in place by two or more drops of solder on the back side, as at *d*, Fig. 2.

Sunken second-dials are well known; but they have usually been made by making a depression in the principal dial and then setting a molding around the edge of the depression.

By making the second-dial and its margin in one and the same piece it is more readily prepared than when the graduation and figuring are required in the depression in the principal dial, and the second-dial in a single piece is secured in the opening in the principal dial with much greater facility than the detached border-molding can be.

I claim—

A clock-dial having an opening made therein for the second-dial, combined with a second-dial having a molded edge formed in the same piece with the dial, and so as to set into the opening in the principal dial, the edge of the second-dial overlapping onto the surface of the principal dial, substantially as described.

L. E. JEROME.
